A. G. HOOVENS

LIGHTNING ROD ANCHOR

Filed April 10, 1922

Inventor,

A. G. Hoovens.
E. W. Anderson, Jr.
Attorneys

UNITED STATES PATENT OFFICE.

AMASA G. HOOVENS, OF GOSHEN, INDIANA.

LIGHTNING-ROD ANCHOR.

Application filed April 10, 1922. Serial No. 551,170.

To all whom it may concern:

Be it known that I, AMASA G. HOOVENS, a citizen of the United States, resident of Goshen, in the county of Elkhart and State 5 of Indiana, have made a certain new and useful Invention in Lightning-Rod Anchors; and I declare the following to be a full, clear, and exact description of the same, such as will enable others skilled in the art to which 10 it appertains to make and use the invention, reference being had to the accompanying drawings, and to letters or figures of reference marked thereon, which form a part of this specification.

15 Figure 1 is a perspective view of the invention as applied.

Figure 2 is a side view of the invention, showing the lowering rod and the hole in the ground engaged by the anchor.

20 Figure 3 is a similar view with said rod removed and the anchor tilted.

Figure 4 is a detail end view of the anchor.

Figure 5 is a cross section taken through 25 the cable and the metal tie or wrapping.

Figure 6 is a view similar to Figure 1 and showing the hook device in substitution for said tie or wrapping.

The invention has relation to improvements in anchors for lightning rod and other 30 cables, the object being to provide an improved practical and efficient device for the purpose.

The invention consists in the novel construction and combinations of parts, as hereinafter set forth.

In the accompanying drawings illustrating the invention, the numeral 1 designates the lightning rod cable, and 2 is the anchor 40 of brass or other suitable material, and the body of which is straight and laterally extended by means of lateral flanges 4, 4, and having reduced twin straight rod-form end portions in line with said body and having 45 oppositely beveled ends 3, 3, each beveled upon one side only. The said body of the anchor is provided with a central eye extension 5, and with end shoulders 6, 6.

The copper cable 1 has its ground end 50 engaged with the eye 5, and the free end of the cable may be secured to the cable body by a metal tie or wrapping 7, as in Figure 5 of the drawings; or the ground end of the cable may have a suitable hook device 8 secured thereon as at 9, said hook device being of suitable metal of some flexi-

bility and having interfitting lugs or extensions 10, 10, hammered in upon the cable and to effect a secure engagement therewith, as in Figure 6.

In the use of the invention, a hole is made in the ground by a pointed iron bar or other means to a depth of from eight to ten feet to permanent moisture, the hole being sufficiently large to permit the passage 65 of the anchor with the cable attached thereto, and this bar being withdrawn, the lightning rod cable and anchor in parallel relation are lowered down the hole, a rod 11 having a longitudinal recess 12 at its lower 70 end engaging the uppermost end portion of the anchor down to the shoulders 6, 6, of the uppermost portions of the lateral flanges, said rod serving to hold the anchor and cable parallel while being lowered down into the 75 hole, the lower pointed portion of the anchor aiding in the engagement of the anchor with said hole so that the anchor may be readily pushed down the hole.

The rod 11 is then withdrawn, leaving the 80 anchor at the bottom of the hole and the cable thereto attached.

Either of the straight end portions of the device and either end shoulder thereof is adapted for engagement with the ground 85 imbedding tool and is also adapted to penetrate the ground straight downwardly when pressure is exerted thereon by said tool, the anchor being reversible when attached to the cable to present either end thereof uppermost.

The device being imbedded in the ground, upward strain upon the cable causes the uppermost end of the anchor which is beveled oppositely to that of the lowermost end to 95 engage the side of the aforesaid hole fulcrumwise to tend to turn the anchor to a position at right angles to the cable.

Both end portions of the anchor being alike, either end may be uppermost when 100 lowered down into the ground, and the anchoring action will be precisely similar in either case. The anchor assumes a position at right angles to the cable under strain for full resistance, as shown in Figure 1. The 105 cylindrical rod like end portions of the anchor having plane beveled ends provide for very strong points, which owing to their location upon the opposite side of the anchor from the eye 5 facilitate their engagement with the ground. The eye extension 5 is in the plane of the rod form body of the

device or in the plane of the longitudinal axis of said body, whereby the bight of the cable end as in Figure 1 will engage said eye extension in a manner to admit of the reversal of the anchor end for end, and in a manner to admit of the anchor being moved pivotally upon said bight to a position parallel with the cable as in Figure 2.

I claim:

- 10 1. An anchor for lightning rod and other cables, consisting of an elongated laterally extended straight body having a central lateral eye extension for cable attachment and twin straight end portions in line with said body and having oppositely beveled ends each beveled upon one side only and either of which acts as a fulcrum engaging the ground wherein the anchor is imbedded to turn the anchor to right angular position relative to the cable, either of said straight end portions being adapted for engagement with a ground imbedding tool and being also adapted to penetrate the ground straight downwardly when pressure is exerted there-

on by said tool, the anchor being reversible when attached to the cable to present either end thereof uppermost.

2. An anchor for lightning rod and other cables, consisting of an elongated laterally extended straight body having end shoulders and a central lateral eye extension for cable attachment and twin straight rod-form end portions in line with said body and having oppositely beveled ends each beveled upon one side only and either of which acts as a fulcrum engaging the ground wherein the anchor is imbedded to turn the anchor to right angular position relative to the cable, either of said straight end portions and either of said end shoulders being adapted for engagement with a ground imbedding tool and also adapted to penetrate the ground straight downwardly when pressure is exerted thereon by said tool, the anchor being reversible when attached to the cable to present either end thereof uppermost.

In testimony whereof I affix my signature.

AMASA G. HOOVENS.
